[57] CLAIM

The ornamental design for a patio seat, as shown and described.

DESCRIPTION

FIG. 1 is a perspective view of a patio seat showing my new design in the form of an armchair;

FIG. 2 is a front elevation view of the arm chair of FIG. 1;

FIG. 3 is an elevation left side view of the arm chair of FIG. 1;

FIG. 4 is an elevation view of the arm chair of FIG. 1 seen from the rear;

FIG. 5 is a top view of the arm chair of FIG. 1 showing that the front bar of the seat is larger than the others;

FIG. 6 is a bottom view of the arm chair of FIG. 1;

FIG. 7 is an elevational right side view of the armchair; and,

FIG. 8 is a perspective view of the bench showing that the only difference between the armchair and the bench resides in the length of the seat and the back.
